UNITED STATES PATENT OFFICE.

JOSEPH HABART, OF CLEVELAND, OHIO, ASSIGNOR TO THE BANKERS SAVINGS & CREDIT SYSTEM COMPANY, OF CLEVELAND, OHIO, A CORPORATION OF OHIO.

COIN BANK.

Application filed September 19, 1924. Serial No. 738,715.

This invention relates to coin banks or receptacles, and more particularly to an improved guard for the coin admitting slots of receptacles of this class.

8 The invention has for its objects to provide a highly efficient coin slot guard that is infallible of operation and is immune from disorder and that is so designed and constructed as to expedite and cheapen manufacture and facilitate assembly.

In the accompanying drawing, Fig. 1 is a section through a coin bank or receptacle incorporating my improved coin slot guard; Fig. 2 is a section on the line 2—2 of Fig. 1; 15 Fig. 3 is a view similar to Fig. 1 showing the bank or receptacle inverted; Fig. 4 is a detail of the coin slot guard; Fig. 5 is a perspective view of one of the tumblers of the guard; and Fig. 6 is a similar view of the support or casing for the tumblers.

The coin bank or receptacle, designated 1 in the drawing, may be of any approved type, the one shown having an open side that is surrounded by an inset flange 2 against 25 which the edge portion of a removable wall or closure 3 is adapted to seat, the wall or closure 3 being shown as secured to said flange by a lug 4 and the bolt 5 of a lock 6 which engage the inner side of the flange at diametrically opposite points. The lug 4 and lock 6 are secured to the wall 3 as by 30 rivets 7. The wall or closure 3 may be removed by retracting the bolt 5 and swinging the side of the wall or closure which carries the lock outwardly after which the lug 4 may be readily disengaged laterally from the flange 2.

The wall or closure 3 is provided with a coin admitting slot 10. Shown as carried on 40 the inner side of the wall or closure 3 and over the slot 10 is a rectangular or box-like support or casing 11 which is preferably formed of a single piece of sheet metal. This support or casing comprises what I 45 shall term a top wall 12, side walls 13 and end walls 14, the side and end walls being turned downwardly from the top wall, and at their lower edges the side walls are provided with extensions that are turned laterally to form ears 14 which have perforations registering with perforations in the wall or closure 3 for the reception of rivets 15 which secure the support or casing to said wall or closure. The lug 4 is held from

55 turning on the rivet 7 by being extended inwardly and secured by the adjacent rivet 15. The top wall 12 has a slot 16 which is of about the same dimensions as the coin slot 10 and is in alignment therewith.

Housed within the support or casing 11 are 60 tumblers 18. These tumblers are preferably identical with one another and therefore interchangeable, and each is comprised of a head 19 and parallel branches 20. The head consists of something more than half a square 65 and the branches 20 are spaced equal distances from an axis that is oblique with respect to the square. Along the opposite sides of the slot 16 in the top wall 12 and along the side walls 13 are transverse slots 70 22 constituting guides within which the branches 20 of the tumblers are slidable. These slots, as will best be seen in Fig. 4, have their ends inclined and parallel to the 75 oblique axes of the support or casing which bisect the angles between the top wall 12 and the side walls 13. It will be further observed, especially in Fig. 2 that the slots which guide the tumblers along one side of the support or casing 11 are staggered with 80 respect to those of the other side.

Both the support or casing 11, and the tumblers 18, are adapted to be die stamped from sheet metal which assures uniformity 85 of product and accuracy of dimensions, and in assembling the guard, the workmen takes from a supply of tumblers the required number and drops them into a support or casing with their branches 20 occupying the slots or guides 22. He then applies the casing to 90 the wall or closure 3 and secures it thereto by the rivets 15 and the work is completed.

When the bank or receptacle is supported 95 with the wall or closure 3 downward, as in Fig. 1, the tumblers 18 gravitate to a position wherein they obstruct the passage between the slot 16 of the support or casing and the coin slot 10 of the wall or closure. With the tumblers in this position it is impossible for a coin to be extracted from the bank, and the fact that the portions of the tumblers wherewith the edge of the coin engages are at right angles to the direction of movement of the coin prevents the coin from exerting any lateral pressure on the tumblers 100 which would tend to separate the tumblers enough to allow the coin to enter between them and force them apart. Upon an in-

version of the bank, as in Fig. 3, the tumblers 18 fall apart and a coin may be readily inserted through the slots 10 and 16.

Having thus described my invention, what I claim is:—

1. In a coin bank, in combination with a wall having a coin slot, a support disposed adjacent said wall and comprising angularly disposed parts on each side of the coin slot, 10 said parts having guide slots which are parallel to axes bisecting the angles between said parts, and tumblers having branches that are slidable within the guide slots, the tumblers being movable on the aforesaid oblique axes into and out of coin obstructing position.
2. In a coin bank, in combination with a wall having a coin slot, a support disposed adjacent said wall and incorporating side 20 walls and a top wall, the top and side walls being at right angles to each other, the top wall having a coin slot in alignment with the first mentioned coin slot, the top and side walls having guide slots which are parallel 25 to axes bisecting the angles between the top and side walls, and tumblers having branches that are slidable within the guide slots, the tumblers being movable on the aforesaid oblique axes into and out of coin obstructing position.
3. In a coin bank, in combination with a wall having a coin slot, a box-like casing carried by the inner side of said wall and incorporating a top wall that is spaced from 30 and substantially parallel with the former

wall and having a coin slot that is substantially in alignment with the former coin slot, said casing having side walls that are substantially at right angles to the top wall, the top and side walls having transversely 40 aligned guide slots the axes whereof are parallel to oblique lines bisecting the angles between the top and side walls, and a plurality of tumblers housed within the casing and having branches that are slidable within 45 the guide slots, the guide slots along one side of the casing being staggered with respect to those along the other side.

4. In a coin bank, in combination with a wall having a coin slot, a box-like casing carried by the inner side of said wall and incorporating a top wall that is spaced from 50 and substantially parallel with the former wall and having a coin slot that is substantially in alignment with the former coin slot, 55 said casing having side walls that are substantially at right angles to the top wall, the top and side walls having transversely aligned guide slots the axes whereof are parallel to oblique lines bisecting the angle between the top and side walls, and a plurality of tumblers housed within the casing and having branches that are slidable within the 60 guide slots, the tumblers having coin abutting edges which are at substantially right 65 angles to the direction of passage of a coin through the coin slots.

In testimony whereof, I hereunto affix my signature.

JOSEPH HABART.
